SWINGING WINDOW AND SCREEN MOUNTING

Filed Aug. 17, 1928

UNITED STATES PATENT OFFICE

EARLE W. CUMMINGS, OF SANTA BARBARA, CALIFORNIA, ASSIGNOR TO WATERTITE
CASEMENT HARDWARE CO., OF SANTA BARBARA, CALIFORNIA, A CORPORATION
OF CALIFORNIA

SWINGING WINDOW AND SCREEN MOUNTING

Application filed August 17, 1928. Serial No. 309,197.

This invention relates to hinged or swinging window mountings of the casement variety and particularly to the special mounting of casement windows in the same frame with 5 hinged or swinging screen frames.

The objects of the invention are to provide a mounting of the character described which will facilitate operation of the sash and/or screen, permit reaching all sides of 10 both screen and sash from within the building, provide a unit fixture easy to apply, avoid the use of casement adjusting rods in most installations, provide a single locking handle which locks a sash together with 15 screen by a single turn of the handle, provide means for moving the sash to any position either in or out through movement of the screen frame, as well as other features of improvement which will appear in the drawings and are described in the following specification.

Briefly described the invention comprises mounting a screen frame and a window sash for outward swinging, the screen frame positioned inwardly of the sash and provided with a latch whereby it may be made to latch the sash at any position of swinging and cause both sash and screen to swing together, and may be unlatched from the sash after the 20 sash has been pushed or pulled open to the degree desired. Also such mounting of a screen frame and sash in relation to the window frame so as to provide arm space between sash and window frame, and between 25 screen and sash, so that all sides of sash and screen may be reached for cleaning when the window sash is opened.

In the drawings accompanying this specification Fig. 1 is an elevation of my window and screen combination as seen from inside of 40 a building and with sash and screen closed.

Fig. 2 is an enlarged cross-section of the combination as seen from the line 2—2 of 45 Fig. 1, but with the window sash and screen open.

Fig. 3 is an enlarged vertical section of the lower portion of Fig. 1 as seen from the line 3—3 thereof.

Fig. 4 is an enlarged fragmentary section 50 of the central portion of Fig. 1 showing the

latch arrangement on the right hand sash and right hand screen frame.

Fig. 5 is an enlarged edge view of one of the pivoting fixtures showing the spring washer under the lever arm to produce a 55 tight friction joint for holding the sash in any adjusted position of opening.

In the drawings 1 is the window sill, 2 the window frame side pieces, 27 the top or head piece, 3, 3' the outwardly swinging sash, 4, 60 the outwardly swinging screen frame and 4' a fixed screen frame screwed or nailed in place in the window frame.

The frame, sill and head piece are formed with several steps to provide spaced stops as 65 at 5 for the sash and 6 for the screen frame, so that when both sash and screen frames are closed a space will exist between them as best shown in Fig. 3.

Both of the sash frames and one of the 70 screen frames are mounted to swing outwardly on pivoted levers secured to top and bottom of the frames and to the sill and head piece of the window frame as indicated in Fig. 2, the several steps in the sill and head 75 piece; and the sash frames being longer than the screen frames; provide for the screen frame and its levers swinging outwardly and crossing over the levers of the sash without interference when both sash and screen are 80 open as shown in Fig. 2.

The mountings for the sash comprise each 85 two levers or flat metal links 7, 8 pivoted at opposite ends to flat metal plates 9—10 secured respectively to the sash and the window frame. Plates 9 lie each in a rabbet 11 formed along the upper and lower edge of the sash, and plates 10 lie against a step formed on the head piece and sill and also bear endwise against a spaced block 12 on 90 head piece and sill all of which serves for quickly positioning the parts correctly when installing.

The pivotal joints of the mounting are frictionally retarded by means of a spring 95 split washer interposed between the joint members as indicated at 26 in Fig. 5.

The lengths, and position of the levers are such as to swing the sash from closed position against stop 5 to open position as indi- 100

cated by sash 3' in Fig. 2 and when so open the window is stopped from further opening by lever 7 bearing at its edge along the rabbet 11.

5 The pivotal mounting for screen frame 4 is practically the same as the mounting for the sash above described and consists of levers 13, 14 pivoted to plates 15, 16, tho the spring washers are preferably omitted from 10 the pivotal joints as it is not necessary to frictionally hold the screens in open position as it is the sash frames. Sill plate 16 of the screen mounting is preferably located in a recess in the step of the sill or an extra stool 15 covers it in the manner indicated.

Swinging screen frame 4 locks to hook 17 projecting from fixed frame 4' by means of a turnable handle 18 mounted on frame 4 and provided at its outer end with a latch arm 19, the engaged position of the members 20 being indicated in Fig. 1.

Sash 3' is provided with a pair of locking cams 20 which are manually turned to engage a recess plate in sill and head piece as indicated in Fig. 1 where the lower corner of screen frame 4' is broken off to clearly show the lower cam. Sash 3' is also provided with a fixed cam latch plate 21 adapted to be simultaneously engaged by latch arm 19 when sash 3' is closed as indicated in Fig. 4 25 so that when sash 3' is secured with cam locks 20 it will form a rigid member against which screen 4 and sash 3' may be locked by latch arm 19, and thereby avoid making the relatively frail screen frame 4' form the only anchor.

Through the arrangement shown screen frame 4 locks simultaneously against frame 4' and sash 3' when the latter is closed.

40 Sash 3 is manipulated and also locked by means of screen frame 4 by the provision of a latch hook 22 pivotally mounted in the fitting plate 23 on the screen frame and operated by the thumb piece 24, arranged to engage a short bar 25 extending horizontally on and secured to the sash as indicated in Fig. 2.

This bar 25 is long enough to be engaged by the hook 22 at any position of the sash 50 and screen regardless of the lateral displacement of hook 22 relative to sash on account of the two different arcs traversed by sash and screen frame, as the hook will slide along the bar while window sash is being pushed 55 outwardly or pulled inwardly.

In operation, to open sash 3, the screen frame 4 is unlatched and pushed outwardly to force the window sash before it to desired position. The latch hook 22 is then released 60 from bar 25 on sash by pressure on thumb piece 24 and the screen is closed and locked, or if desired the other sash 3' may be released and pushed outwardly by hand, and screen frame 4 then closed and locked.

65 Sash frame 3' is always opened or closed

by reaching it with the hand when screen 4 is opened, and sash 3' may also be cleaned on its inner face when fully or partly open, and on its outer face when closed.

The outer side of sash 3 is reached through 70 the space between the frame and sash when the latter is open, and the inner side is easily reached by releasing the screen latch 22 from the sash and swinging the screen parallel with the sash as indicated by the dotted 75 position of the screen frame, and which provides plenty of room between outside of screen and inside of sash for cleaning either.

To close the sash 3 when screen 4 is closed the latter is first opened until its hook 22 80 engages the bar on the sash and whereupon the sash may be pulled entirely closed by means of handle 18 and by a slight turn of the handle both sash and screen are securely locked.

85 It is, of course, evident without an additional drawing that my sliding hook and bar arrangement 22-25 will work on a sash and screen wherein the sash is hinged with common hinges to the window frame instead of 90 by means of the lever mounting shown, or if both sash and screen are hinged with common hinges but in the latter case there would not be any arm space for cleaning between screen and window sash, which is one of the objects 95 of the invention.

It is also apparent that in addition to the spring washer retarded joints of the pivot levers any of the well known casement sash stabilizing adjusters may be used if desired 100 without in any way affecting the invention.

I claim:

1. A window sash provided with pivotal 105 mountings adjacent one edge whereby it may be swung outwardly from a window frame, a screen frame positioned in the window frame to the inner side of said sash provided with pivotal mountings adjacent one edge whereby it may also be swung outwardly from said window frame, and means manually operable from the inside of the screen adapting said sash to be engaged and released from said screen at any point of swinging of the sash.

2. A window sash provided with pivotal 115 mountings adjacent one edge whereby it may be swung outwardly from a window frame, a screen frame positioned in the window frame to the inner side of said sash provided with pivotal mountings adjacent one edge whereby it may also be swung outwardly from said window frame, and means on said screen frame adapted to automatically engage said sash upon swinging the screen toward said sash.

3. In a structure as specified in claim 1, the mountings of sash and screen being so spaced relative to one another as to provide an arm space between sash and screen accessible from the mounted edges of the sash and 130

screen when both sash and screen are open outwardly.

4. A window sash provided with means whereby it may be swung outwardly from a window frame, a screen frame positioned in the window frame to the inner side of said sash provided with means whereby it may also be swung outwardly from said window frame, the mountings of sash and screen being so spaced relative to one another as to provide an arm space between sash and screen accessible when both are open.

5. A window sash provided with means whereby it may be swung outwardly from a window frame, a screen frame positioned in the window frame to the inner side of said sash provided with means whereby it may also be swung outwardly from said window frame, both above mentioned means comprising links pivotally secured to the edges respectively of the sash and screen and to the window frame so arranged that the links of the screen will cross those of the sash when swinging the screen.

6. A window sash provided with means whereby it may be swung outwardly from a window frame, a screen frame positioned in the window frame to the inner side of said sash provided with means whereby it may also be swung outwardly from said window frame, both above mentioned means comprising links pivotally secured to the edges respectively of the sash and screen and to the window frame so arranged that the links of the screen will cross those of the sash when swinging the screen and means on the pivotal joints of the links of the sash whereby they will work under greater friction than those of the screen.

7. A window sash provided with means whereby it may be swung outwardly from a window frame, a screen frame positioned in the window frame to the inner side of said sash provided with means whereby it may also be swung outwardly from said window frame, both above mentioned means comprising links pivotally secured to the edges respectively of the sash and screen and to the window frame so arranged that the links of the screen will cross those of the sash when swinging the screen, and a sill member on the window frame covering the pivotal ends of the links of said screen.

8. A window frame provided with a pair of outwardly swinging casement windows A and B, a pair of screen frames C and D mounted in the window frame to the inner side of windows A and B respectively, means provided whereby screen frame C may be swung outwardly, together with or after outward swinging of window A, means for locking window B closed, and means provided for simultaneously locking window A and screen C to window B and screen D.

9. A window and screen frame combina-

tion comprising a window frame provided with a pair of outwardly swinging casement sashes, a screen frame in back of one of the sashes mounted for outward swinging, a screen frame in back of the other sash fixedly secured in place.

10. A window and screen frame combination comprising a window frame provided with a pair of outwardly swinging casement sashes, a screen frame in back of one of the sashes mounted for outward swinging, a screen frame in back of the other sash fixedly secured in place and means for simultaneously locking the two sashes and the screen frames.

11. In combination with a pair of adjacently pivoted sash and screen frames swinging along different arcs in opening, a latch on one frame directed toward the other frame, a bar on said other frame extending along the same parallel to the plane of swinging and of a length to be engaged by said latch at various points of the swinging so as to provide for said different arcs of swinging.
